COMMUNION CUP TRAY

Gordon R. Davis, 8729 Orion, El Paso, Tex. 79904

Original design application Jan. 2, 1974, Ser. No. 429,716,
now Patent No. 238,329. Divided and this application
Dec. 9, 1975, Ser. No. 640,231

Term of patent 14 years

Int. Cl. D7—01

U.S. Cl. D7—17

Fig. 1

Fig. 2

Fig. 3

Fig. 4

FIG. 1 is a top perspective view of a communion cup tray showing my new design;

FIG. 2 is a bottom perspective view thereof;

FIG. 3 is a side elevational view thereof; and

FIG. 4 is a top plan view thereof with the cover removed for convenience of illustration.

This is a division of design application Ser. No. 429,716, filed Jan. 2, 1974, now Pat. No. D. 238,329.

I claim:

The ornamental design for a communion cup tray, substantially as shown and described.
